PUMP

Calvin C. Williams, Philadelphia, Pa.

Application July 3, 1944, Serial No. 543,253

1 Claim. (Cl. 103—144)

1

This invention relates to an improved rotary pump and while being especially intended for use as a blower in pumping gaseous fluids, such as air, may also be used with equal facility for pumping liquids.

Among other objects, the invention seeks to provide a pump wherein a gain in displacement will be had over a comparable pump having a cylindrical casing of an internal diameter equal to the distance between aligned blades from tip to tip.

A further object of the invention is to provide a pump wherein the tips of the blades will be caused to follow a somewhat elliptical path, thereby to obtain a greater displacement of the pump as compared with like blades travelling in a circular path.

Still another object of the invention is to provide a pump wherein the pump casing will, throughout the major portion of its interior, be of somewhat elliptical contour conforming to the travel of the tips of the blades, but wherein the somewhat elliptical inner surface of the casing will be interrupted at one point by an arcuate seat accommodating the periphery of the rotor and cooperating therewith to form a working seal between the inlet and the outlet of the pump.

A further object of the invention is to provide a pump wherein substantially no friction will occur between the tips of the blades and the casing so that the pump may be operated at high speeds and adapting the structure for use as a prime mover, if so desired.

And the invention seeks, as a still further object, to provide a pump wherein the discharge pressure thereof may be varied.

Other and incidental objects will appear during the ensuing description of the invention, and in the drawings:

Figure 1 is a vertical longitudinal sectional view through my improved pump.

Figure 2 is a transverse section on the line 2—2 of Figure 1.

Figure 3 is a transverse section on the line 3—3 of Figure 1.

Figure 4 is a transverse section on the line 4—4 of Figure 1.

Figure 5 is a detail plan view of the rotor.

Figure 6 is a fragmentary perspective view of one of the blades.

Figure 7 is a detail section on the line 7—7 of Figure 1.

Figure 8 is a detail perspective of the fixed crank shaft employed.

Figure 9 is a diagrammatic view showing the

2

somewhat elliptical interior of the casing and the arcuate rotor seat.

Figures 10, 11 and 12 are diagrammatic views showing the movement of the blades.

5 In carrying the invention into effect, I employ a casing 10 open at its ends and provided with a base 11 as well as with an inlet 12 at one side thereof and an outlet 13 at its opposite side. Disposed in the inlet is a valve 14 which may be rotatably adjusted for regulating the intake of air, for instance, and varying the discharge pressure of the pump.

15 Detachably fixed to the casing 10 at one end is an end cap 15 having a hub 16, and detachably fixed to the casing at its opposite end is an end cap 17 having a hub 18. Extending within the casing from the cap 15 is a fixed crank shaft 19, seen in detail in Figure 8 of the drawings, and, as will be observed, this shaft is provided at one end with a long terminal 20 while at the opposite end of the shaft is a short terminal 21 aligned with the terminal 20. The shaft is further provided with spaced cranks 22 having aligned pins 23, while the outer ends of said pins are reduced 20 to form necks 24. Rigidly fixed to the hub 16 of the end cap 15 is a detachable end plate 25 having a sleeve 26 through which the terminal 20 of the shaft 19 extends, and locking the shaft in said sleeve is a key 27. The shaft will thus be 25 rigidly supported to extend in fixed position within the casing 10.

20 Mounted to turn about the axis of the shaft 19 is a hollow cylindrical rotor 28 which, as seen in Figures 2 and 3 of the drawings, is provided at 35 quadrantly spaced points with chordal thickened portions 29 having slots 30 therethrough, and bracing the rotor internally are medial webs 31. Formed on the rotor at one end is a hub 32 having a sleeve 33 which freely but closely surrounds 40 the terminal 20 of the shaft 19, and formed on the rotor at its opposite end is a somewhat larger hub 34 having a sleeve 35, the outer end of which lies flush with the terminal 21 of the shaft. Fixed 45 within the hub 16 of the cap 15 is a bearing 36 which surrounds the sleeve 33 and rotatably supports the rotor at one end, and fixed within the sleeve 35 is a bearing 37 which surrounds the terminal 21 of the shaft 19 and rotatably supports the rotor at its opposite end.

50 It is now to be noted that the rotor 28 is split at the plane of one pair of the slots 30 into like complementary mating sections so that the rotor may be assembled about the pairs of blades later to be described, and formed on the hubs 32 and 34 of the rotor are mating bosses 38. Engaged

through said bosses are cap screws 39 detachably securing the sections of the rotor together.

Extending through the hub 18 of the end cap 17 of the casing 10 is a drive shaft 40 aligned with the axis of the shaft 19, and formed on the drive shaft is a head 41 which snugly fits over the outer end of the sleeve 35 of the hub 34 of the rotor 28 and seats against said hub. Detachably securing the head to the hub are cap bolts 42. Fixed in the hub 18 is a bearing 43 which rotatably supports the drive shaft, and detachably secured to the outer end of said hub is an end plate 44 surrounding the shaft. Thus, power may be applied to the shaft 40 for turning the rotor. Formed through the terminal 20 of the shaft 19, as best seen in Figure 8 of the drawings, is a duct 45 so that oil may be introduced into the casing, and disposed about said terminal and about the shaft 40 are washers 46 of felt or the like to prevent leakage.

Mounted upon the crank pins 23 of the shaft 19 are bearings 47, and in this connection it is to be observed that the outer side plates of the cranks 22 of the shaft are beveled at their ends so that the bearings may be slipped over the terminals of the shaft and over said plates to be thus installed. Fitting the necks 24 of the pins are sectional stop collars 48 blocking outward displacement of the bearings, and detachably securing said collars in position are split spring rings 49. Fitting the outer race rings of the bearings are square cross-heads 50.

Cooperating with the crossheads 50 are pairs of oppositely disposed blades 51 which are slidably received through the slots 30 of the rotor 28, and, as will be noted, the thickened portions 29 of the rotor will provide a correspondingly wide bearing area between the walls of said slots and the blades. Formed on the blades at their inner edges, as particularly seen in Figure 6, are mating yoke sections 52 which straddle the shaft 19, and detachably connecting said sections are bolts 53, it being observed, as best brought out in Figure 1, that the yokes of one pair of blades are staggered with respect to the yokes of the other pair of blades. The blades of each pair of blades are thus rigidly united to form a solid unit so that each blade of each pair will balance the other blade of each pair and tend to counteract the effect of centrifugal force on the blades. Thus, the blade units are balanced and may be rotated at high speed. Formed on the inner edges of the blades at the ends thereof are saddle plates 54 which slidably fit against the edges of the crossheads 50 to coact therewith and connect the blades with said crossheads.

Attention is now directed to Figure 9 of the drawings. A circle is shown at 55. This circle has a center 56 which represents the axes of the crank pins 23 of the shaft 19. A point 57 represents the axis of the shaft and, consequently, the center of rotation of the rotor, indicated on the diagram by a circle 58. The distance between the points 56 and 57 in a straight line is the distance which the bearings 47 are eccentric with respect to the center of rotation of the rotor and is the diameter of a circle 59. Struck from points on this circle, say fifteen degrees apart more or less, as suggested by the radial lines on the diagram, is a somewhat elliptical curve indicated at 60, which curve coincides with the circle 55 at the area designated 61. The curve 60 represents the contour of the inner surface of the casing 10, except at that area represented between the points 62 and 63 on the diagram. Between the points 62 and 63, the inner surface of the casing is cut

away to form an arcuate seat indicated at 64. This seat is of substantially the same radius, or slightly more, say a few thousandths or so, than the radius of the periphery of the rotor 28 and is struck from the point 57 as a center. Accordingly, said seat is curved to fit the periphery of the rotor with which it coacts to form a working seal between the rotor and the casing throughout a relatively wide arcuate area lying between the inlet 12 and the outlet 13 of the casing 10. For the purposes of this disclosure, I have indicated the area of the seal as extending for thirty degrees between the points 62 and 63 but as will be understood, the area of the seal may, of course, be varied. It is important, however, to provide, instead of straight line contact as would otherwise occur between the rotor and casing in the absence of the seat 64, a relatively wide seal since, as will be explained, the tips of the blades 51 will follow the curve 60 between the points 62 and 63 so that said seal must alone serve to cut off communication between the inlet and the outlet of the casing.

Referring now to Figures 10, 11 and 12 of the drawings, reference letters will be used to avoid confusion with the reference numerals of the other figures of the drawings. One of the crossheads 50 is indicated at A and the top and bottom edges thereof, as viewed in Figure 10, at B and C respectively. A blade unit comprising one pair of the blades 51 is indicated at D, one pair of the saddle plates 54 thereof at E, and the top and bottom edges of one of the yokes between the blades of said unit at F and G respectively. The rotor 28 is indicated at H and an arbitrary point thereon at I. The points 56 and 57 as well as the circle 59, as used in Figure 9, remain the same in Figures 10, 11 and 12 and are so designated. Explanation of the movement of one pair of blades 40 will suffice for both pairs of said blades.

Assuming now that the blades D stand in the horizontal position shown in Figure 10, it will be seen that the longitudinal center of the blade unit is disposed at the point 57 on the circle 59 while the plates E are at the edge B of the crosshead A. As the rotor H turns, the plates E of the blade unit will, by the action of the rotor on the blades, be shifted along the crosshead while the longitudinal center of the blade unit will travel around the circle 59 until, when the point I on the rotor has traveled ninety degrees and the blades D have reached a vertical position, as shown in Figure 11, the longitudinal center of the blade unit will be at the point 56 on said circle, 55 so that the plates E will be at a middle position on the crosshead.

As the rotor H further turns and the point I on the rotor has traveled one hundred eighty degrees and has reached the position shown in Figure 12, the longitudinal center of the blade unit will have completed its travel from the point 56 around the circle 59 to again lie at the point 57. As will be observed, the edge B of the crosshead A is now at the bottom and the edge C at the top 65 while the edge F of the yoke of the blades is at the bottom and the edge G at the top. Thus, during one hundred eighty degrees of revolution of the rotor H, the longitudinal center of the blade unit has travelled completely around the circle 59 while the blades have been shifted from one end to the other of the crosshead, it being observed in Figure 12 that the plates E are at the edge C of the crosshead. The cycle will, of course, be repeated during the next one hundred eighty 70 degrees of revolution of the rotor.

As will be perceived in view of the foregoing, the blades D, while being revolved, are not only moved endwise in an arcuate path a distance equal to the diameter of the circle 59, but are also shifted in a straight line path along the crosshead A. This arcuate endwise movement and concurrent straight line sidewise movement of the blades causes the tips thereof to describe, during each one hundred eighty degrees of revolution of the rotor, a path which may be termed somewhat elliptical, which is the curve 60 shown in Figure 9. The tips of the blades will accordingly follow the somewhat elliptical contour of the inner surface of the casing without friction therebetween. Thus, at the area of the seat 64, the tips of the blades will not, as previously mentioned, contact said seat due to the fact that the seat is on a radius of the point 57 and interrupts the somewhat elliptical inner surface of the casing for the width of the seat. As will now also be apparent, the pump will, due to the somewhat elliptical inner contour of the casing, have a greater capacity than a similar pump having a casing of the same size but of cylindrical inner contour.

Having thus described my invention, what I claim is:

A rotary pump including a casing, end caps fixed to the casing and provided with hubs, an end plate carried by the hub of one of said caps, a stationary crank shaft extending into the casing, said shaft being fixed at one end to said plate and being free at its opposite end, a rotor surrounding the shaft and provided with end sleeves, a bearing fixed in the hub of said end cap to coact with one of said sleeves externally thereof and journaling the rotor at one end, a bearing fixed to the free end of said shaft to coact with the other of said sleeves internally thereof and journaling the rotor at its opposite end, a drive shaft journaled through the hub of the other of said end caps and connected to the rotor at the free end of the crank shaft, blades slidably received through the rotor to coact with the casing, and means rotatably mounting the blades on said crank shaft eccentrically of the rotor.

CALVIN C. WILLIAMS.
